UNITED STATES PATENT OFFICE.

WILLIAM F. DIESEL, OF ROCHESTER, NEW YORK, ASSIGNOR TO SARGENT & GREENLEAF CO., OF ROCHESTER, NEW YORK, A CORPORATION OF NEW YORK.

LOCK AND LATCH MECHANISM.

1,188,346.

Specification of Letters Patent. Patented June 20, 1916.

Application filed October 14, 1915. Serial No. 55,889.

To all whom it may concern:

Be it known that I, WILLIAM F. DIESEL, of Rochester, in the county of Monroe and State of New York, have invented certain new and useful Improvements in Lock and Latch Mechanisms; and I do hereby declare the following to be a full, clear, and exact description of the same, reference being had to the accompanying drawings, forming a part of this specification, and to the reference-numerals marked thereon.

My invention relates to improvements in lock and latch mechanisms, and it has for its object the provision of a structure embodying a dead lock in combination with a latch, and so related that the latch serves to control the position of the bolt of the lock.

Another and further purpose of my invention is to reduce to a minimum the number of individual and separate elements required in a structure of this character, and to correlate them in such a way as to make it possible to manufacture the device at a reasonably small cost, at the same time affording an arrangement which can be readily assembled or disassembled, and in which the parts are not likely to in any way get out of order.

An additional purpose of the improvement is to afford a dead lock mechanism in which the bolt can be positively retained in either its inner or outer positions, and so combined with a latch construction that when the bolt is in its innermost position, it is automatically released and moved to its outer or locking position upon operation of the latch, and movement of the latch is always necessary to permit movement of the bolt.

To these and other ends the invention consists in certain improvements and combinations of parts all as will be hereinafter more fully described, the novel features being pointed out in the claims at the end of the specification.

In the drawings: Figure 1 is a horizontal sectional view showing the application of a preferred form of my invention to a door and casing; Fig. 2 is a plan view of the mechanism, showing the position of the parts with the latch and bolt in their outermost and innermost positions respectively; Fig. 3 is a similar view with the latch moved

to its innermost position, and the bolt released for outward movement; Fig. 4 is a similar view with the latch and bolt both in their outermost positions; Fig. 5 is a similar view showing the position of the parts after initial movement of the actuator has caused partial movement of the latch member from the position shown in Fig. 4, releasing the bolt for inward movement; Fig. 6 is a plan view of the housing with parts removed; Fig. 7 is a sectional view on the line *a*—*a* of Fig. 2, and Fig. 8 is a sectional view on the line *b*—*b* of Fig. 2.

Similar reference numerals in the several figures indicate the same parts.

The invention may be carried out in a number of different ways, a preferred example of which is illustrated in the accompanying drawings where the structure is shown applied to a door 1 and a casing 2, to which is attached a keeper 3 that is adapted to receive the bolt in the manner shown in Fig. 1, and also to effect movement of the latch member when the door is closed, through a beveled edge 4, all as will appear more clearly from the detailed description to follow.

The mechanism attached to the door is arranged within a housing 5, and includes a cylindrical hollow bolt 6. The bolt includes a frame 7 which carries a projection 8 for a purpose that will appear presently. The latch member is designated at 9, being movable within the cylindrical bolt 6, and it includes a plate 10, slideable within the sides of the frame 7, and supported in recesses 11 formed between the upper and lower lugs or flanges 23 of the frame 7, as shown in Fig. 7, while the bolt frame carries a pin 12 which rests upon the floor of the housing and maintains the parts in proper relation. Mounted on a post 13 is a locking device preferably in the form of a pivoted detent 14 carrying a pin 15 coöperating with a cam slot 16 in the latch member, and 17 is a nose formed on the detent and arranged to engage on opposite sides of the projection 8 of the bolt, whereby to hold the bolt in either its inner or outer position against movement until the latch member is operated. Movement of the latch member inwardly causes the pin 15 to be moved lengthwise of the slot 16 from the position shown in Fig. 2 to that shown in

Fig. 3; thus swinging the locking device away from engagement with the bolt and permitting free movement of the latter. If the bolt happens to be in its inner position, 5 upon closing the door, the latch will be moved inwardly, as already described, to release the bolt which is thereupon moved to its outer position by a spring 18 mounted on the post 19 and engaging a wall of the housing and a pin 20 on the bolt frame; and when the bolt is in its outermost or locked position, provision is made for releasing the locking device or detent 14 by inward movement of the latch through an actuator that I 10 will describe more fully a little later.

The locking device or detent 14 co-operates on opposite sides of the projection 8 for retaining the bolt. Thus when it is on one side of the projection 8, it holds the bolt in 15 its outer position, as in Fig. 4, and when on the opposite side, it retains the bolt in its inner position, as in Fig. 2. The latch member is held in its normal position through the action of a spring 21 mounted on the aforementioned post 19 with one end in engagement with the latch member and the opposite end in engagement with the pin 15 of the detent, causing the latch member to be actuated under normal conditions to the position 20 shown in Figs. 2 and 4. The actuator for unlocking the bolt embraces a rotary plate 22, the opposite ends of which are arranged for engagement with the aforementioned lugs or flanges 23 formed on the bolt frame, 25 as shown in Figs. 4 and 7. The actuator 22 is controlled by a tumbler lock mechanism 24 which may be of any desirable form, and includes a rod 25 that is operatively connected to the actuator for moving the same so that 30 when the tumbler mechanism is operated by insertion of a proper key, the actuator will be turned to release the bolt 6. To this end, the plate 22 includes cam surfaces 26, between which is a recess 27 that receives the 35 pin 12 when the parts are positioned as shown in Fig. 4. Upon the initial movement of the actuator, one of the cam surfaces 26 engages a pin 12, moving the latch member inwardly far enough to release the locking 40 device from engagement with the bolt, while its further movement causes the bolt to be moved by engagement of the actuator with the flanges 23 on the bolt frame, as shown in Fig. 5. The bolt may be released from the 45 other side of the door without the aid of a key by a correspondingly formed actuator 28 which is connected to and operated by a handle in the form of a knurled head 29 arranged on the outside of the housing. In 50 case it is desired to retain the bolt permanently in its inner position, I provide a positive stop, consisting of a slide member 30, which carries a projection 31 adapted to be moved into the path of the bolt frame by a 55 finger piece 32. The slide 30 carries a series

of recesses 33 with which co-operates a spring pin 34 for frictionally holding it in either position of adjustment.

The operation of the structure may be described briefly as follows: With the parts in 70 normal position, as shown in Fig. 2, the bolt being in its inner position, upon closing the door the latch 9 is forced inwardly, releasing the locking device from engagement with the bolt frame after which both the 75 latch member and bolt are moved outwardly by their respective springs, and the bolt is locked in its outer position by the detent 14. The lock may be opened either from the outside through the key controlled tumbler lock 80 mechanism, or from the inside by turning the handle 29, initially causing inward movement of the latch member, and thereby moving the locking device or detent 14 out of 85 engagement with the bolt frame, after which the bolt is free to be moved to its innermost position by continued turning of the actuator, and the parts are then in the position shown in Fig. 2 ready for another operation.

I claim as my invention:

1. The combination with a hollow locking bolt, of a latch member movable within the bolt, and means controlled by the latch member acting to retain the bolt in its inner or outer position.

2. The combination with a hollow cylindrical locking bolt, of a cylindrical latch member movable within the bolt, and a locking device arranged to engage the bolt and retain it in position, the latch member acting, during its initial inward movement, to release the locking device and permit movement of the bolt.

3. The combination with a hollow locking bolt, of a latch member movable within the bolt, means controlled by the latch member acting to retain the bolt in its inner or outer position, and a stop adapted to be adjusted into the path of the bolt to prevent its movement.

4. The combination with a hollow locking bolt, of a latch member movable within the bolt, a locking device arranged to engage said bolt and retain it in either its inner or outer position, the latch member having a pin and slot connection with the locking device whereby the latter is removed from engagement with the bolt upon inward movement of the latch member.

5. The combination with a hollow cylindrical locking bolt, of a cylindrical latch member movable within the bolt, and means controlled by the latch member acting to hold the bolt against outward movement and operable to permit such movement.

6. The combination with a hollow cylindrical locking bolt, of a cylindrical latch member movable within the bolt and a locking device arranged to engage the bolt to retain it against outward movement and re-

leasable upon movement of the latch member.

7. The combination with a hollow cylindrical locking bolt, of a cylindrical latch member movable within the bolt, and a locking device arranged to engage the bolt to retain it against movement in either direction and releasable upon movement of the latch member.

10 8. The combination with a hollow cylindrical locking bolt, of a cylindrical latch

member movable within the bolt, and a locking device arranged to engage the bolt to retain it in either its inner or outer position and adapted to be engaged by said latch member, the latter acting when moved inwardly to actuate the locking device out of engagement with the bolt.

WILLIAM F. DIESEL.
